ELECTRICAL WARP STOP MOTION

Application filed July 9, 1930. Serial No. 466,709.

This invention relates to improvements in electrical warp stop motions and it is the general object of the invention to provide an improved form of electrical contact bar 5 to be used with a drop wire which may be employed either for electrical or mechanical indication.

One well-known form of mechanical warp stop motion which has gone into extensive use is that employing a drop wire having in the upper part thereof a slot the top of which is restricted for the purpose of preventing oscillation of a normally vibrating detector rod, such a drop wire and motion being shown in reissue patent to Regan No. 14,829. The usual form of electric contact bar includes an upwardly projecting live electrode to be located within a drop wire slot to engage an inclined surface thereof. In such motions the live electrode is accessible not only to the fallen drop wire but to the tools or foreign matter which may fall across them.

It is an important object of my present invention to inclose the live electrode so that all but a small surface thereof will be guarded and at the same time proportion the live and shielding or grounded electrodes so as to cooperate with a drop wire of the Regan type.

The drop wires are arranged in parallel banks separated by relatively heavy bars and it is another object of my invention so to relate the separator bars and the electrodes of the contact bar that when a drop wire is in its maximum angular position with regard to its normal vertical axis there will be no opportunity for electrically connecting the two parts of the contact bar unless a drop wire be fallen. In such an arrangement it is not necessary that the live electrode shall lie entirely within the outline of the inclosing electrode, but it is desirable that it shall project somewhat beyond the top of the shielding electrode so that by a camming action resulting from the restricted top of the drop wire slot the two electrodes may be connected.

With these and other objects in view which will appear as the description proceeds, my

invention results in the combination and arrangement of parts hereinafter described and set forth in the claims.

In the accompanying drawing wherein a convenient embodiment of my invention is set forth,

Fig. 1 is a side elevation of a warp stop motion having bars made according to the preferred form of my present invention, said bars and other parts being in vertical section,

Fig. 2 is an enlarged vertical transverse section through the contact and separator bars, shown in Fig. 1,

Fig. 3 is an end elevation of part of the structure shown in Fig. 2,

Fig. 4 is similar to a portion of Fig. 2 but with the drop wire shown in circuit closing position, and

Fig. 5 shows a contact bar of modified form.

Referring to Fig. 1 the loom frame 10 has a bracket 11 secured thereto in which is adjustably held a vertical post 12. A supporting threaded rod 13 is held by a set screw 14 in fixed relation with respect to the post and has strung therealong a plurality of units 15 between which are located separator bars 16 located below the rod 13. The units are formed as shown in Fig. 1 to provide suitable supports for the contact bars to be described hereinafter. The matter thus far described is in common use and may be used in conjunction with any suitable electrically operated stopping device including suitable circuits and sources of power.

My invention relates more particularly to the contact bar designated generally at 20 and in carrying the preferred form of my invention into effect I provide an outside inclosing shield member 21 which may have a vertical wall 22 to lie against a portion of the supporting unit 15 and may have the top thereof bent over and down as at 23. The bottom of said shield may be bent horizontally as at 24 and then upwardly as at 25 and bent back again so as to have a vertical portion 26 nearer the wall 22 than the extreme upward part of the lower rounded edge 25. The latter wall may if desired be in sub-

stantial alignment with the free end or edge 27 of the top of the shielding electrode. The shield is clamped between adjacent units and therefore held to the loom frame.

- 5 The live element 30 has a lower vertical portion 31 lying between the lower vertical wall 26 and the vertical part 22 of the shield and has an outwardly bent portion 32 provided with a surface 33 located preferably 70 beyond the top edge or surface 27 of the shield electrode. The upper edge of the live contact is located between the parts 22 and 27 so that said live electrode is held against 75 transverse motion in all directions with respect to the shield. Any suitable form of insulation such as properly prepared oiled sheets of paper 40 shown in Fig. 2 may be employed to separate the live and grounded electrodes of the bar.

- 20 Under normal conditions with the drop wire in the position shown in Fig. 2 the warp W will support the drop wire so that the same will be out of contact with the live electrode. The rounded portion 25 of the shield electrode 80 may have contact with the inner edge 50 of the slot 51 of the drop wire D without danger of closing a circuit. The usual restricted part 52 of the drop wire slot defines a shoulder 53 which effectively separates the edge 50 from 85 the live electrode. The right hand separator bar 16 as viewed in Fig. 2 prevents tilting of the drop wire so that the edge 50 at no time can have simultaneous contact with the live and grounded electrodes while the drop wire 90 is supported by the warp. So far as this feature of my invention is concerned it is immaterial whether the live electrode projects beyond the outline of the shielding electrode.

- It is desirable to have surface 33 project 95 beyond the surface 27 so that when the drop wire falls to the position shown in Fig. 4 the restricted slot 52 will cause the shoulder 53 to cam over the portion 32 and have contact with the surface 33 and the opposite edge 100 of the slot will be drawn against the vertical face 22 of the outer electrode. In this way electrical connection of the two electrodes results and establishes a condition which closes a circuit, not shown, to effect a change 105 in the operation of a loom, such, for instance, as stopping the loom. It is to be understood that when warp is in proper condition the shoulder will always be above the exposed 110 part of the live electrode.

- 55 In the modified form shown in Fig. 5 the rounded portion 25 is replaced by a horizontal laterally extending edge 60 which projects as shown sufficiently to one side of the contact bar to hold the edge 50 of the drop wire 115 slot spaced from the live electrode.

- From the foregoing it will be seen that I have provided an electrical warp stop motion having a contact bar so formed as to co-act with the type of drop wire having a slot the upper part of which is restricted.

It will also be seen that the live electrode projects beyond the upper part of the shielding electrode and is the means by which lateral movement of the drop wire is effected to connect the bar electrodes electrically. Furthermore, because of the relation between the separator bars 16 and the component parts of the contact bar the drop wire will be held from ever electrically connecting the two electrodes so long as the drop wire is held 70 in raised position. Also, in both forms of the invention a projection extending laterally from the outer electrode holds the edge 50 of the drop wire from contact with the live electrode. In both forms of the invention the lateral extension, whether the rounded edge 25 or edge 60, is so placed relatively to the separator bars as to permit a lateral movement of the drop wire in the direction of said lateral extension when the shoulder 80 85 90 95 100 105 110 115 120 125 130 135 140 145 150 155 160 165 170 175 180 185 190 195 200 205 210 215 220 225 230 235 240 245 250 255 260 the same polarity, a drop wire having a slot with vertical walls the lower of which are farther apart than the upper walls, the walls being symmetrically placed relatively to the vertical central axis of the drop wire.

4. In an electrical warp stop motion having a plurality of individually removable supporting units, a contact bar for each unit having two insulated oppositely charged electrodes one on one lateral face of the bar and the other on the other lateral face of the bar, one of the electrodes extending around both edges of the other electrode, and a drop wire having a slot through which the bar passes, said slot having a lower wide part and an upper narrower part, the distance between the aforesaid lateral faces being less than the width of the lower part of the slot and greater than the width of the upper part of the slot.

5. In an electrical warp stop motion having a plurality of individually removable supporting units, a live electrode, a grounded electrode with an exposed surface and extending around the edges of the live electrode and formed to expose a surface to the latter, a drop wire having a slot through which the electrodes pass, the slot having an upper part narrower than the distance between the surfaces of the electrodes and a lower part wider than said distance, the drop wire when fallen electrically connecting the surfaces, and means to hold that part of the drop wire near the lower part of the slot normally spaced from the live electrode, said means and exposed surface of the live electrode lying on the same side of a vertical line drawn through the center of the bar.

6. In an electrical warp stop motion, a live electrode, a grounded electrode with an exposed surface and extending around the edges of the live electrode and formed to expose a surface of the latter, a drop wire having a slot through which the electrodes pass, the slot having an upper part narrower than the distance between the surfaces of the electrodes and a lower part wider than said distance, the drop wire when fallen electrically connecting the surfaces, and means to hold that part of the drop wire near the lower part of the slot normally spaced from the live electrode, said means being formed as part of and projecting laterally from the grounded electrode.

7. In an electrical warp stop motion, a live electrode, a grounded electrode with an exposed surface and extending around the edges of the live electrode and formed to expose a surface of the latter, a drop wire having a slot through which the electrodes pass, the slot having an upper part narrower than the distance between the surfaces of the electrodes and a lower part wider than said distance, the drop wire when fallen electrically connecting the surfaces, and means to hold that part of the drop wire near the lower part of the slot normally spaced from the live elec-

trode, said means being formed as part of and projecting laterally from the grounded electrode, the said exposed surface of the live electrode lying within the outline of the grounded electrode.

8. In an electrical warp stop motion having a plurality of individually removable supporting units, a live electrode, a grounded electrode with an exposed surface and extending around the edges of the live electrode and formed to expose a surface of the latter, a drop wire having a slot through which the electrodes pass, the slot having an upper part narrower than the distance between the surfaces of the electrodes and a lower part wider than said distance, the drop wire when fallen electrically connecting the surfaces, and means to hold that part of the drop wire near the lower part of the slot normally spaced from the live electrode, said means being formed as part of and projecting laterally from the grounded electrode and located below the live electrode surface.

In testimony whereof I have hereunto affixed my signature.

OSCAR V. PAYNE.
